REFRIGERATING APPARATUS

Harry B. Hull, Dayton, Ohio, assignor to General Motors Corporation, Dayton, Ohio, a corporation of Delaware

Application November 20, 1935, Serial No. 50,722

3 Claims. (Cl. 62—129)

This invention relates to refrigerating apparatus and particularly to means for removing moisture, dripping from a cooling element or evaporator of a refrigerating system, from the refrigerating apparatus.

Various devices have been provided for collecting and removing moisture dripping from an evaporator in a refrigerator in which the machinery compartment is located below the food storage compartment. In such devices, moisture has been conducted by gravity to the machine compartment where it may be dissipated or removed therefrom in several different ways.

It has now become common in the construction of mechanical refrigerators or refrigerating systems and particularly refrigerators of the room cooling type to locate the condenser of the system above other elements thereof and to extend the condenser through a window or opening in the wall of the room of the building in which the room cooling apparatus is located. This arrangement is provided so that the condenser will be exposed to atmosphere exteriorly of the building and cooled by the outside atmosphere.

An object of the present invention is to remove moisture dripping from a cooling element of a refrigerating system by means which applies pressure to the body of water flowing from the cooling element.

Another object of the present invention is to provide an improved means or device for causing moisture dripping from a cooling element of a refrigerating system to flow away from the refrigerating apparatus to a point where it may be removed from the apparatus under conditions where gravity drainage is not available.

A further object of the invention is to provide an improved means or device for causing drip water flowing from a cooling element of a refrigerating apparatus to be trapped and lifted or conducted upwardly of the various elements of the apparatus and particularly upwardly of the drip water receiving or collecting means intermittently in response to the weight of the collected or trapped body of water.

In carrying out the foregoing objects, it is a still further object of the invention to provide an improved means or device for causing drip water flowing from the cooling element or dehumidifier unit of a room cooling or conditioning apparatus to be lifted or conducted upwardly of the various elements of the apparatus and to direct the drip water over the condenser of the apparatus, located exteriorly of the room in

which the apparatus is located, to augment cooling of the condenser by atmospheric air.

Further objects and advantages of the present invention will be apparent from the following description, reference being had to the accompanying drawings wherein a preferred form of the present invention is clearly shown.

In the drawings:

Fig. 1 is a vertical sectional view through a building and a refrigerating apparatus within a room in the building adapted to cool and cause circulation of air about the room;

Fig. 2 is a vertical sectional view through a portion of the refrigerating apparatus employed to elevate and dispose of drip water flowing from the cooling element of the apparatus;

Fig. 3 is an enlarged fragmentary top plan view of a portion of the structure shown in Fig. 2 and is taken on the line 3—3 thereof; and

Fig. 4 is a sectional view of the portion of the apparatus shown in Fig. 3 and taken on the line 4—4 thereof.

Referring to the drawings, and particularly to Fig. 1 thereof, there is shown a refrigerating apparatus of the type usually referred to as a room cooling or conditioning apparatus. The refrigerator or room cooling apparatus is disposed in a room 10 provided in a building 11. The refrigerator or room cooling apparatus includes a cabinet generally represented by the reference

character 12. Cabinet 12 comprises a framework which is covered by a shell or by vertically disposed metal panels 13. The top of cabinet 12 is covered by a closure member 14 having a plurality of louvered passages 15 provided therein. An electric motor 16 is mounted within cabinet 12 adjacent the top 14 thereof and is operatively connected to a fan or blower 17. The one face of blower or fan 17 is located within an opening 18 provided in a housing or shroud 19. An evaporator 21 of a refrigerating system, to be presently described, is mounted within cabinet 12 below housing or shroud 19 and fan 17. The sides of the shell or the side panels 13 of cabinet 12 are provided with a plurality of openings (not shown) to permit fan or blower 17 to draw air into the cabinet. Operation of the fan or blower 19 by motor 16, in response to any suitable or desirable control means, causes air to be drawn into the cabinet 12 through the openings in the side walls thereof. This air is caused to flow over and/or through the cooling element or evaporator 21 by fan or blower 17 and is drawn into the housing or shroud 19. The refrigerating effect produced by the evaporator 21 cools the

5

55

air and the cooled air is expelled from the cabinet 12 through the louvered openings 15 into the room 10. This action of that portion of the apparatus thus far described creates a circulation of air within room 10 and causes the warmer air therein to enter the cabinet 12 through the openings (not shown) and to be cooled and dried by the room cooling apparatus for increasing the comfort of occupants of the room.

5 The refrigerating system associated with the room cooling apparatus includes, in addition to the cooling element or evaporator 21, a compressor 23 operatively connected, through suitable belt and pulley connections 24, to an electric motor 25. Operation of compressor 23 by motor 25 causes gaseous refrigerant or refrigerant evaporated within the cooling element 21 to be withdrawn therefrom through the refrigerant conveying conduit 26. The compressor 23 compresses the gaseous refrigerant and forwards same under pressure, through conduit 27, to a condenser 28. The condenser 28 may be of any suitable or conventional construction and is preferably mounted within a housing or shroud 29 having an opening 31 in the top wall thereof and an opening 32 provided in the bottom wall thereof. The housing or shroud 29 is preferably secured to the back wall 13 of cabinet 12 and extends through a window or opening 33 provided in the wall of room 10 or building 11. Suitable blocks or the like 34 surround the housing 29 to seal the opening 33 through which the housing extends. Any suitable partition or closure member 35 may be provided within the housing 29 to prevent the ingress of atmospheric air, from the outside of building 11, into the room 10 through the housing or shroud 29. A fan 36 operated by an electric motor 37 and mounted on brackets 38 within housing or shroud 29 may be employed for circulating atmospheric air externally of building 11 through the shroud 29 and over the condenser 28 for cooling the compressed refrigerant circulated thereto by the condenser 23. The refrigerant cooled and liquefied in condenser 28 flows through the pipe 41 into a receiver-reservoir 42 where it is stored prior to being conducted, through pipe 43, to the evaporator 21 to cause the evaporator to produce a refrigerating effect. An expansion device or valve 44, of any suitable or conventional design, is interposed in the conduit 43 for controlling the flow of liquid refrigerant to the cooling element 21. The expansion device or valve 44 is operated by movement of a diaphragm or bellows contained therein and having a conduit connection 45 with a thermostat bulb 46 in response to expansion and/or contraction of a volatile fluid sealed within the thermostatic system. To effect expansion and/or contraction of the fluid within the thermostatic system and opening or closing of the expansion valve 44, the bulb 46 is secured in intimate thermal contact to the conduit 26 leading from the evaporator 21. Operations of the motor 25 of the refrigerant liquefying and circulating unit, motor 16 connected to fan or blower 17 and motor 37 connected to fan 36 may be controlled in any suitable and well known manner to those skilled in the art.

In cooling and causing circulation of the air 10 within room 10 in the manner described, it is obvious that the air upon being cooled will cause withdrawal of moisture therefrom and will cause the moisture to be deposited upon the coils or refrigerant conduits of the evaporator 21. After 75 a predetermined amount of moisture accumulates

on the evaporator, it flows therefrom and must be conveyed to a point exteriorly of room 10 in order to prevent rehumidifying of the air in the room. I provide a pan or the like 51 and position this pan below the cooling element 21 so that the moisture will flow in the form of drip water thereinto. The bottom of pan 51 slopes downwardly to a conduit connection 52, which conduit conveys the drip water from the pan into a device, generally represented by the reference character 53 and, having a pipe 54 leading upwardly therefrom to a water distributing header 55 mounted above the condenser 28 for a purpose to be hereinafter more fully described. The device 53 is mounted beneath the top wall of 15 the machine compartment of the room cooling apparatus 12 by suitable brackets 56.

The device 53 is a means for removing drip water, flowing from the cooling element or evaporator 21, upwardly of the drip pan 51, device 53 20 and other elements of the refrigerant liquefying and circulating unit to a point above the condenser 28 and, therefore, this device conveys the drip water from the refrigerating apparatus and exteriorly of the room 10 and building 11. The 25 device 53 includes a casting 60 enclosed within and secured to the casing or covering 61 (see Fig. 2) which is secured to the cabinet 12 by the brackets 56. Casting 60 of device 53 includes a vertically disposed portion 62 having an integral 30 hub 63 extending horizontally therefrom. Hub 63 forms a pivot for an arm 64 having a collar portion 65 which surrounds the hub. The hub 63 is provided with two hollowed-out or drilled openings 66 and 67 which are connected to and communicate with the pipes or conduits 52 and 54 respectively. Openings or passages 68 and 69 communicating with and extending from the openings 66 and 67, respectively, to the outer cylindrical face of hub 63 are provided for a 40 purpose to be presently described. A nut or the like 71 (see Fig. 3) may be secured to hub 63 in any suitable and well known manner to hold the arm 64 upon the hub. The arm 64 has an opening 72 extending therethrough and communicating with the interior of a closed receptacle or tank 73 which is secured to the free movable end of the arm. A branch conduit or passage 74 leads from opening or passage 72 in arm 64 to the inner cylindrical face of the collar portion 50 65 thereof. It will be noted that the distance between the opening or passage 72 and the opening or passage 74 at the face of the inner surface of collar portion 65 are spaced a shorter distance apart than the openings or passages 68 and 69 55 provided in the hub 63. The reason for the difference in spacing of these passages at the point described, will become apparent in the explanation of the operation of the device. The collar portion 65 of arm 64 is provided with an outwardly extending lug or cam 76. A pressure applying means in the form of a pivotally mounted arm 77 having a roller 78 secured thereto is provided with a spring 79 for forcing the roller 78 into engagement with the collar portion 65 of arm 64 and the roller 78 is disposed in the path of movement of the lug or cam 76. When movement of arm 64 is affected, the pressure applied to the arm by the spring 79 causes the arm to be quickly moved into its lower or upper position 70 by movement of cam 76 beyond the roller 78. A sealed glass tube 81 containing mercury and having electric contacts 82 and 83 sealed thereto and extending into the tube 81 forms a switch which is secured by a bracket 84 to arm 64 (see 75

Fig. 2). The arm 64 and can or receptacle 73 are normally maintained in their upper position as shown in Fig. 2 of the drawings by a spring 85 which overcomes the weight of the arm and the receptacle. One end of spring 85 is secured to a bracket 86 bolted or otherwise fastened to a horizontally extending portion 87 of casting 60. A finger 88 secured to can or receptacle 73 is adapted to engage the bracket 86 to limit or stop the upward movement of arm 64 at a predetermined point. A closed tank or sealed container 89 mounted upon the portion 87 of casting 60 has an electric resistance coil 91 positioned therein and mounted upon a suitable insulating block 15 and which coil forms a heater for heating and causing expansion of air within the tank 89. The top wall of receptacle 73 has a fitting 92 provided therein for receiving one end of a flexible conduit 93. The opposite end of the conduit 93 is secured to a fitting 94 provided in one wall of the sealed or closed tank 89. The resistance coil forming the heater 91 is connected in series with an electric circuit (not shown) leading to the contacts 82 and 83 and is adapted to be energized when the electric circuit is completed by mercury in tube 81 bridging the contacts 82 and 83.

It is to be understood that while I have illustrated my invention in combination with a room cooling apparatus wherein water withdrawn from the air being cooled by the cooling element or evaporator of a refrigerating system drips therefrom and is caused to be elevated above the drip water catching or collecting means and caused to flow over the condenser of the refrigerating system, my invention is also useful in all other installations of refrigerating systems where the drip water cannot be removed from the apparatus by gravity flow therefrom. For example, my improved apparatus may be disposed in a room or apartment located above another room or apartment through which a gravity flow water conveying drain pipe cannot be extended, thus necessitating the drip water to be elevated and then conveyed by gravity through a conduit or pipe which extends downwardly through an elevator shaft provided in the building or which extends downwardly on the exterior of the building.

When moisture or water drips from the cooling unit or air dehumidifier 21, located in the cabinet 12 of the apparatus, this moisture or drip water is conveyed by pan 51, conduit 52, passages 66 and 68 in the hub 63 of device 53, and passage 72 into the can or receptacle 73. As the level of water collected in the receptacle 73 rises to a predetermined point in can or receptacle 73, the weight of the drip water overcomes the weight of arm 64 and the tension of spring 85 and causes the arm and receptacle 73 to move downwardly about the pivot hub 63. In moving downwardly the arm causes the top of cam 76 to ride past the roller 78 and the tension of spring 79 thus augments the downward movement of arm 64 to cause a quick movement thereof. This movement of arm 64 moves the passage 72 formed therein out of communication with the passage 68, passage 66 and conduit 52 and also moves the branch passage 74 in arm 64 into communication with the passage 69, passage 67 and conduit 54. The downward movement of arm 64 furthermore causes the mercury in tube 81 to flow into contact with contacts 82 and 83 so as to bridge same and complete the electric circuit through the heater coil 91. Energization of the coil 91 causes same to produce a heating effect in the sealed tank or

compartment 89. Air within the tank 89 is expanded upon being heated by the resistance coil 91 and flows through the flexible conduit 93 into the closed water receptacle 73. The heated air creates a pressure upon or above the body of drip water in receptacle 73 and causes the water to be expelled therefrom through the passages 69 and 67. The conduit 54 communicating with passage 67 conveys the water upwardly of the water removing device 53 and other elements of the refrigerating apparatus to the distributing header 55 positioned above the condenser 28 of the refrigerating system. The drip water removed from and upwardly of the receptacle 73 may be directed to a drain, but it is preferable in the present invention to cause this water to be distributed over and in contact with the various pipes or conduits comprising the condenser 28 to cool the condenser or to augment cooling thereof. For example, the drip water may be distributed by header 55 over the condenser 28 so that air circulated through the shroud or housing 29 by fan 36 will evaporate the water into the atmospheric air to augment cooling of the condenser by the air.

After the drip water collecting receptacle 73 has been substantially emptied of its water content, the spring 85 again returns the arm 64 to the position shown in Fig. 2 of the drawings. The upward movement of arm 64 by spring 85 causes the mercury in tube 81 to flow out of contact with the electric contacts 82 and 83 to thus break or open the electric circuit to the heating coil 91. Air trapped within the receptacle 73, conduit 93 and tank 89 again cools and is backed up into the tank 89 by further flow of drip water from the cooling element 21 through conduit 52, passage 66, passage 68 and passage 72 into the receptacle 73. It being understood, of course, that the branch passage 74 of passage 72 is out of communication with the passages 69 and 67 and conduit 54 when the device 53 is in a position to receive drip water from conduit 52. Obviously the water removing cycles of the device 53 as described continue periodically as long as water is dripping from the cooling element and directed into the collector or receptacle 73 of the device.

It will be apparent that I have provided an effective and improved means for elevating drip water, flowing from an evaporator of a room cooling apparatus, to a point above the apparatus, where the water may then flow by gravity to a drain without attention on the part of the user of the apparatus. My improved means permits the drip water flowing from an evaporator of a room cooling apparatus to be utilized for augmenting the cooling of the condenser of the refrigerating system, which condenser may be located above other elements of the refrigerating system and extended through an opening or window of the room above the apparatus. I thus eliminate the necessity of manually emptying a drain pan of a room cooling apparatus and this is particularly advantageous in apartments or office buildings where at times there is no attendant in the building. My invention also eliminates the necessity of extending a gravity flow drain pipe through a room located below the room in which my improved apparatus is disposed.

While the form of embodiment of the invention as herein disclosed constitutes a preferred form, it is to be understood that other forms

might be adopted, all coming within the scope of the claims which follow.

What is claimed is as follows:

1. In combination, a portable unitary structure including an element which dehumidifies air and which is adapted to have water dripping therefrom, means connected to a source of energy for circulating a fluid through said element to cause same to dehumidify the air, means for catching the drip water from said element, said drip water catching means having an inlet for conveying the drip water thereinto and an outlet adapted to conduct drip water therefrom, means for closing said inlet and for creating a pressure in said drip water catching means, said last named means including means disposed in the air above water in said catching means and deriving energy from said source of energy for said fluid circulating means for heating and expanding the air above the water in said catching means, and a conduit connected to said outlet and extending upwardly above said drip water catching means, said pressure creating means being effective to force water from said drip water catching means through said conduit.
2. In combination, a portable unitary structure including an element which dehumidifies air and which is adapted to have water dripping therefrom, means connected to a source of energy for circulating a fluid through said element to cause same to dehumidify the air, means for catching the drip water from said element, said drip water catching means having an inlet for conveying the drip water thereinto and an outlet adapted to conduct drip water therefrom, means for closing said inlet and for creating a pressure in said drip water catching means, said last named means including means disposed in the air above water

in said catching means and deriving energy from said source of energy for said fluid circulating means for heating and expanding the air above the water in said catching means, and a conduit connected to said outlet and extending upwardly 5 above said drip water catching means, said pressure creating means being normally ineffective and rendered effective automatically in response to the flow of a predetermined amount of drip water from said element to said catching means 10 to force water from said drip water catching means through said conduit.

3. In combination, a portable unitary structure including an element which dehumidifies air and which is adapted to have water dripping therefrom, means connected to a source of energy for circulating a fluid through said element to cause same to dehumidify the air, means for catching the drip water from said element, said drip water catching means having an inlet for 15 conveying the drip water thereinto and an outlet adapted to conduct drip water therefrom, means for closing said inlet and for creating a pressure in said drip water catching means, said last named means including means disposed in the air 20 above water in said catching means and deriving energy from said source of energy for said fluid circulating means for heating and expanding the air above the water in said catching means, and a conduit connected to said outlet and extending 25 upwardly above said drip water catching means, said pressure creating means being normally ineffective and rendered effective automatically in response to the weight of water accumulated in said catching means to force water therefrom 30 through said conduit.

HARRY B. HULL.
